(57) **CLAIM**

The ornamental design for a toy gun, as shown and described.

DESCRIPTION

FIG. 1 is a perspective view of the toy gun showing my new design;

FIG. 2 is a perspective view thereof from another angle;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof;

FIG. 8 is a bottom plan view thereof;

FIG. 9 is an enlarged view of portion 9 of FIG. 2; and,

FIG. 10 is an enlarged view of portion 10 of FIG. 4.

The broken lines shown in the figures are for the purpose of illustrating portions of the toy gun and form no part of the claimed design.
